UNITED STATES PATENT OFFICE

OTTO J. HLAVATY, OF CHICAGO, ILLINOIS

DESIGN FOR A PLAQUETTE

Application filed August 21, 1930. Serial No. 36,727. Term of patent 14 years.

To all whom it may concern:

Be it known that I, OTTO J. HLAVATY, a citizen of the United States, residing in Chicago, in the county of Cook and State of Illinois, have invented a new, original, and ornamental Design for a Plaque, of which the following is a specification, reference being had to the accompanying drawing, forming a part thereof.

The figure is a plan view of the plaque showing my new and original design.

The drawing of a side view of my design would disclose a straight heavy line, since the plaque of this application is relatively thin.

I claim:

The ornamental design for a plaque or like object, substantially as shown and described.

OTTO J. HLAVATY.
